UNITED STATES PATENT OFFICE.

DAVID LEWIS, OF SCRANTON, PENNSYLVANIA.

TRAVERSE GUIDE AND THREAD CLEANER.

Application filed May 20, 1924. Serial No. 714,647.

To all whom it may concern:

Be it known that I, DAVID LEWIS, a citizen of the United States, and a resident of Scranton, in the county of Lackawanna and State of Pennsylvania, have invented a new and Improved Traverse Guide and Thread Cleaner, of which the following is a full, clear, and exact description.

This invention relates to thread guides for spooling and winding machines and has for an object to provide an improved construction of guide adapted to be mounted on the traverse bar of the machine, the construction being such that the thread is not only properly guided but large knots and waste are removed.

Another object of the invention is to provide a guide in which adjustable blades are presented for regulating in a certain sense the size of the thread or yarn passed therebetween.

A still further object, more specifically, is to provide a traverse guide for silk thread or yarn wherein the same is caused to pass over porcelain rolls or bars and between blades having square corners which act as cleaning members.

In the accompanying drawing—

Figure 1 is a top plan view of a guide disclosing an embodiment of the invention, the same being shown on an enlarged scale and in connection with part of a traverse bar.

Figure 2 is a side view of the structure shown in Figure 1.

Figure 3 is a sectional view through Figure 1, approximately on line 3—3.

Figure 4 is a sectional view through Figure 1, approximately on line 4—4.

Referring to the accompanying drawing by numerals, 1 indicates the traverse bar of a machine which is of the usual construction and 2 indicates the body of the guide, which body is provided with thickened enlarged members 3 and 4. The body 2 is provided with a groove 5 whereby the same may straddle and properly rest on the bar 1. A groove 6 is provided in the upper part of the body 2 and extends the full length of the body except at the center where the body is cut away down to a line with or below the groove. The body 2 and the members 3 and 4 are preferably formed of aluminum because of the lightness thereof though these parts could be formed of any desired metal. However, it will, of course, be noted that aluminum is comparatively soft and the

thread or yarn passing thereover would soon cut into the body 2. To obviate or prevent this, rolls or bars 7 and 8 of porcelain are provided, said bars guiding the thread so that the same will not touch either the body 2 or the members 3 and 4. A pair of cleaning blades 9 and 10 are mounted in the members 3 and 4 and extend downwardly into the groove 6. These members are preferably beveled or chamfered off at points 11 and 12 and are normally positioned near each other as shown in Figure 2. It will be noted that an aperture 13 is arranged in each of the blades 9 and 10 whereby they may be readily adjusted toward and from each other notwithstanding the fact that the fillister head screws 14 and 15 extends therethrough. A suitable socket 16 is provided in each of the head screws, said sockets being formed to receive a wrench whereby these screws may be tightened at any time for drawing the bifurcated upper part of members 3 and 4 toward each other and thereby gripping or clamping the blades in position. In order to positively lock these blades against accidental shifting, suitable set screws 17 and 18 are provided, said set screws being formed with sockets 19 formed to receive a wrench of a special structure whereby the device is made substantially tamper-proof. By providing clamping means of this kind, it would be impossible to separate the blades without releasing the set screws and also the fillister head screws and in order to do this a proper wrench is essential. This is important in that it permits a foreman or head workman to set the blades and at the same time prevents other workmen from changing the blades in order to allow the yarn to run more smoothly. If the blades were changed the size and character of the yarn would be consequently varied and the standard output would be lowered.

What I claim is:

1. A thread guide for spooling and winding machines, comprising a body adapted to fit on the traverse bar of the machine, said body having a pair of spaced upstanding members, said members being bifurcated, the opening between said members extending downwardly into said body, said body having a slot in the upper part registering with said opening, a pair of cleaning blades mounted in said opening, means for clamping said blades rigidly in place, said blades

being adjustable toward and from each other, and a porcelain bar arranged on each side of said body and in such a position as to receive and guide the silk passed between 5 said blades.

2. A thread guide for spooling and winding machines, comprising a body provided with a pair of spaced upstanding members, said upstanding members being slotted, a 10 blade arranged in each of said upstanding members, each of said blades having a large aperture therein, a screw carried by each of said upstanding members, said screws extending through the apertures in the respective blades for pulling the parts of said upstanding members together and thereby clamping said blades in different adjusted 15 positions to vary the opening therebetween, and a wearing member carried by said body 20 on each side of the body and in line with the opening between said blades.

3. A thread guide for spooling and winding machines, comprising a body formed

with a groove in the lower face for fitting the traverse bar of the winding machine, 25 said body having a slot in the upper edge extending from one end to the other, a pair of cleaning plates positioned so as to extend into said slot, a plurality of clamping members for rigidly clamping said plates in 30 different adjusted positions, and porcelain members carried by the body on opposite sides of said plates and in line with the opening therebetween.

4. A thread guide for spooling and winding machines, comprising a pair of slotted supports, a cleaning and guiding plate mounted in each of the slots of said slotted supports, said plates being adjustable toward and from each other, means for locking said 40 plates in different adjusted positions, and a porcelain member on opposite sides of said supports arranged in line with the opening between said plates.

DAVID LEWIS.
